OIL BURNER WITH VAPORIZING TYPE PILOT

Filed Jan. 13, 1944

UNITED STATES PATENT OFFICE

2,393,233

OIL BURNER WITH VAPORIZING TYPE PILOT

James L. Breese, Santa Fe, N. Mex., assignor to
 Oil Devices, Santa Fe, N. Mex., a limited partnership of Illinois

Application January 13, 1944, Serial No. 518,045

4 Claims. (Cl. 158—91)

My invention relates to an improvement in liquid fuel burners and has for one purpose to provide an improved pilot light for such burners.

Another purpose is to provide an improved pilot light of the generator or vaporizing chamber type.

Another purpose is to provide means for governing the supply of fuel to such a pilot light.

Another purpose is to provide unitary means for controlling the flow of fuel to a pot type burner and for controlling a separate flow of fuel to a pilot light for such burner.

Other purposes will appear from time to time throughout the specification.

My invention is illustrated more or less diagrammatically in the accompanying drawing, wherein—

Figure 1 is a vertical section;

Figure 2 is a partial section along the line 2—2 of Figure 1.

Like parts are indicated by like characters throughout the specification and drawing.

Referring to the drawing, 1 generally indicates a burner pot having a bottom 2 and a top flange 3 surrounding the open mouth of the pot. The flange 3 is shown as resting on an angle ring 4 within an outside housing 5. The upper portion 6 of the outside housing 5 may serve to enclose or form a combustion chamber or radiating element. Any suitable means not herein shown may be employed for supporting the burner. 7 is a centrally apertured flame ring partially closing the otherwise open top of the pot. 8 is a fuel chamber connected to any suitable source of liquid fuel by a fuel pipe 9. The chamber is provided with a removable cover 10. 11 is a fuel pipe extending from the bottom of the float chamber 8 to the fitting 12 which in turn is in communication with the interior of the pot 1. Thus fuel from the float chamber 8 flows along the pipe 11 and out upon the bottom 2 of the pot, where the liquid fuel is vaporized by the heat of combustion in or above the pot. Air for combustion is provided by a plurality of primary air inlets 13 arranged circumferentially about the pot 1 and located at various distances above the bottom of the pot. In practice and assuming that the burner is burning at high fire, the primary air admitted through the air inlets 13, forms with the vaporized fuel, a primary mixture which rises in the pot. It receives a secondary supply of air through a plurality of secondary air inlets 14, herein shown as arranged in a single row about the top of the pot 1 and as having upwardly and inwardly inclined axes which converge toward the center of the pot. Any suitable means may be employed

for manually controlling the supply of fuel which flows along the pipe 11. I illustrate a manual control element 15 which may control any suitable valve not herein shown for varying the rate of flow of fuel from the float chamber 8 to the pot 1.

16 is a vaporizing chamber which may be secured to the pot 1, for example by the bracket 17 and the screws 18. It is aligned with an aperture 19 in the pot 1, through which extends an inlet duct 20, the interior of which is in communication with the interior of the chamber element 16. I find it advantageous to shape the inlet duct 20 in such fashion as to cause it to direct the pilot flame downwardly toward the bottom of the pot at an area adjacent the entry of fuel on the pot bottom from the fitting 12. The interior of the chamber 16 is connected with the interior of the float chamber 8 adjacent the bottom of both elements, by a fuel pipe 21. The level of the fuel in the chambers 8 and 16 may be controlled by a float 22 which is associated with a bell crank lever 23, 24, the upper arm 24 of which presses against a horizontally axised valve element 25 which is normally urged toward the open position by a circumferential spring 26 within the bore 27 of the member 28. 29 is a spring abutment on the valve element 25 and 30 indicates a valve seat surrounding an inlet passage 31 in communication with the fuel pipe 9.

It will be understood that as the level of the fuel in the float chamber 8 drops, the float lowers and permits the spring 26 to move the valve 25 toward the open position. A rise in the liquid level has the opposite effect. A local combustion at the level of the fuel is maintained in the chamber 16, in order to maintain a pilot flame. I illustrate a fixed outer sleeve 35 having an open top and an open bottom extending downwardly into the fuel, through the top of the chamber 16. The sleeve 35 is shown as having longitudinally extending slots 36 which extend both above and below the level of the fuel. It will be understood that the level of the fuel is maintained to prevent any spillage of liquid fuel through the nozzle or inlet duct 20.

37 is a rotatable inner sleeve, shown as open at top and bottom and as having longitudinal slots 38 which also extend above and below the level of the fuel. 39 is any suitable member which serves both to limit the downward movement of the sleeve 37 in the sleeve 35 and for its ready rotation. The structure constitutes a variable air supply means, as air flows down through the open top and interior of the sleeve 37, and the rate of

flow is governed by the rotation of the inner sleeve 37 to vary the air supply passing through the slots 36 and 38. The inner sleeve 37 may be rotated from fully open to fully closed position or may be set at any desired intermediate position.

It will be realized that whereas I have shown and described an operative device, still many changes in size, shape, number and disposition of parts may be made without departing materially from the spirit of my invention, and I wish, therefore, that my showing be taken as in a broad sense diagrammatic.

The use and operation of my invention are as follows:

In hydroxylating pot type burners of the type herein shown, liquid fuel is admitted to the pot, is vaporized by the heat of combustion, receives a primary air supply to produce an incomplete mixture, and is finally burned upon receiving a secondary air supply which completes a fully combustible mixture. The fuel for normal pot combustion is supplied along the pipe 11 and its rate of flow is governed by rotation of the manual control member 15. The liquid fuel flows out upon the bottom 2 of the pot and is there vaporized. As the vaporized fuel rises, it receives primary air through the apertures 13 and secondary air through the apertures 14. It will be understood that the particular pot herein shown is not of itself part of the present invention and is employed as an illustration of a practical structure for use with the pilot and fuel control means herein shown.

The liquid fuel vaporizing chamber 16 is employed to maintain a pilot flame. Combustion is maintained in the chamber 16 at the level of the fuel in order to create sufficient heat to vaporize some of the liquid fuel in the vaporizing chamber. This vaporized fuel, mixing with the air admitted through the sleeve 37 and the slots 36 and 38, supports a flame which flows downwardly into the pot through the nozzle 20. This jet of flame maintains the pot bottom heated locally in the line of inflow of the fuel from the fitting 12. The rate of combustion can be controlled by varying the air supply through the inner tube or sleeve 37. This variation is obtained by rotating the tube to vary the effective openings provided by the slots 36 and 38, the two tubes acting together as a shutter or valve assembly.

I claim:

1. In combination, a vertically axised burner pot having a closed bottom wall, a circumferential side wall and an open top, said circumferential side wall having therein a plurality of primary air inlets spaced circumferentially around the pot and located at various distances from the ends of the pot, means for admitting a secondary air supply adjacent the top of the pot, means for delivering liquid fuel to the interior of the pot for vaporization therein, and an exterior pilot chamber for said pot, the interior of said pilot chamber and said pot being in communication at a level adjacent the level of the lowest of said primary air inlet apertures but above the bottom of the pot, means for delivering liquid fuel to the interior of said pilot chamber for vaporization therein, and means for delivering to the interior of said pilot chamber a controllable air supply.

2. In combination, a vertically axised burner

pot having a closed bottom wall, a circumferential side wall and an open top, said circumferential side wall having therein a plurality of primary air inlets spaced circumferentially around the pot and located at various distances from the ends of the pot, means for admitting a secondary air supply adjacent the top of the pot, means for delivering liquid fuel to the interior of the pot for vaporization therein, and an exterior pilot chamber for said pot, the interior of said pilot chamber and said pot being in communication at a level adjacent the level of the lowest of said primary air inlet apertures but above the bottom of the pot, means for delivering liquid fuel to the interior of said pilot chamber for vaporization therein, and means for delivering to the interior of said pilot chamber a controllable air supply, the level of liquid fuel in the pilot chamber being substantially above the level of liquid fuel in the bottom of the burner pot.

3. In combination, a vertically axised burner pot having a closed bottom wall, a circumferential side wall and an open top, said circumferential side wall having therein a plurality of primary air inlets spaced circumferentially around the pot and located at various distances from the ends of the pot, means for admitting a secondary air supply adjacent the top of the pot, means for delivering liquid fuel to the interior of the pot for vaporization therein, and an exterior pilot chamber for said pot, the side wall of said pot being apertured for communication with the interior of said pilot chamber, a tubular deflector member extending through said aperture, from an upper part of said pilot chamber downwardly into the interior of the pot, said tubular member having a flame discharge orifice located at a level adjacent the level of the lowest of said primary air inlet apertures, but above the bottom of the pot, means for delivering liquid fuel to the interior of said pilot chamber for vaporization therein, and means for delivering to the interior of said pilot chamber a controllable air supply.

4. In combination, a vertically axised burner pot having a closed bottom wall, a circumferential side wall and an open top, said circumferential side wall having therein a plurality of primary air inlets spaced circumferentially around the pot and located at various distances from the ends of the pot, means for admitting a secondary air supply adjacent the top of the pot, means for delivering liquid fuel to the interior of the pot for vaporization therein, and an exterior pilot chamber for said pot, the side wall of said pot being apertured for communication with the interior of said pilot chamber, a tubular deflector member extending through said aperture, from an upper part of said pilot chamber downwardly into the interior of the pot, said tubular member having a flame discharge orifice located at a level adjacent the level of the lowest of said primary air inlet apertures, but above the bottom of the pot, means for delivering liquid fuel to the interior of said pilot chamber for vaporization therein, and means for delivering to the interior of said pilot chamber a controllable air supply.

50

5. In combination, a vertically axised burner pot having a closed bottom wall, a circumferential side wall and an open top, said circumferential side wall having therein a plurality of primary air inlets spaced circumferentially around the pot and located at various distances from the ends of the pot, means for admitting a secondary air supply adjacent the top of the pot, means for delivering liquid fuel to the interior of the pot for vaporization therein, and an exterior pilot chamber for said pot, the side wall of said pot being apertured for communication with the interior of said pilot chamber, a tubular deflector member extending through said aperture, from an upper part of said pilot chamber downwardly into the interior of the pot, said tubular member having a flame discharge orifice located at a level adjacent the level of the lowest of said primary air inlet apertures, but above the bottom of the pot, means for delivering liquid fuel to the interior of said pilot chamber for vaporization therein, and means for delivering to the interior of said pilot chamber a controllable air supply, the level of liquid fuel in the pilot chamber being substantially above the level of liquid fuel in the bottom of the burner pot.

60

6. In combination, a vertically axised burner pot having a closed bottom wall, a circumferential side wall and an open top, said circumferential side wall having therein a plurality of primary air inlets spaced circumferentially around the pot and located at various distances from the ends of the pot, means for admitting a secondary air supply adjacent the top of the pot, means for delivering liquid fuel to the interior of the pot for vaporization therein, and an exterior pilot chamber for said pot, the side wall of said pot being apertured for communication with the interior of said pilot chamber, a tubular deflector member extending through said aperture, from an upper part of said pilot chamber downwardly into the interior of the pot, said tubular member having a flame discharge orifice located at a level adjacent the level of the lowest of said primary air inlet apertures, but above the bottom of the pot, means for delivering liquid fuel to the interior of said pilot chamber for vaporization therein, and means for delivering to the interior of said pilot chamber a controllable air supply, the level of liquid fuel in the pilot chamber being substantially above the level of liquid fuel in the bottom of the burner pot.
